UNITED STATES PATENT OFFICE.

WILLIAM POHLMAN, OF MIDDLETOWN, NEW YORK.

EXPANSION BORING-TOOL.

SPECIFICATION forming part of Letters Patent No. 757,494, dated April 19, 1904.

Application filed February 19, 1903. Serial No. 144,155. (No model.)

To all whom it may concern:

Be it known that I, WILLIAM POHLMAN, a citizen of the United States, residing at Middletown, in the county of Orange and State of New York, have invented certain new and useful Improvements in Expansion Boring-Tools, of which the following is a full, clear, and exact description, such as will enable those skilled in the art to make and use the same, reference being had to the accompanying drawings, forming part of this specification, and wherein—

Figure 1 is a general view of boring-tool; Fig. 2, a section of boring-tool through its center; Fig. 3, a view of boring-tool from lower end; Fig. 4, a view of detached tool-holders, showing plan, side, and end. Fig. 5 shows a position of wedges when annular ring is below the end of the wedges.

My invention relates to that class of boring-tools wherein the cutting-tools are moved laterally from and to the center to suit any intermediate diameters and graduated in such a manner that the diameter of the cutting edges can readily be increased or decreased a known amount (such as one-thousandth part of an inch) by an unskilled workman without the aid of any measuring-tools, each of the cutters being moved universally to the same radius from the center. The number of cutters used is adapted to the size of the boring-tool.

Referring to Figs. 1 and 2, the shank of the boring-tool is shown with a taper end for use in the spindle of a boring-mill or drilling-machine; but a square shank can be substituted when it is desired to operate the tool as a reamer. The body A is formed of one piece with the shank S, the upper part of its outer diameter being furnished with a screw-thread A², (eight threads per inch being used in the present case for convenience of figures, as shown hereinafter.) The screw-threads extend down body A nearly the length of jam-nut R. Laterally through body A and near its lower end are four square openings A', in which move the tool-holders D. Longitudinally of the body A are four recesses or grooves C', in which slide the adjusting-wedges C. These adjusting-wedges, which freely

move vertically in their respective recesses, are provided with screw-threads on their outer surfaces, the diameter and pitch of thread corresponding with those on the outside of the body A, and their lower ends are beveled to an angle 55 of forty-five degrees, declining inward and forming the wedges C'. An annular ring B with threads on its inside is screwed on the body A until it is clear of the threads of same, where it then engages the threads of the vertical 60 wedges C. The lower edge of annular ring B is also beveled at an angle of forty-five degrees on the inside lower edge, forming wedge B'. On the outside of annular ring B are holes B², in which to insert the prongs of a spanner-wrench for adjusting the tool-holders D. To securely hold all parts in their positions when adjusted, a jam-nut R is provided, having similar holes in its outer surface in which to insert wrench, as in the annular ring. In the 65 lateral openings A' are placed tool-holders D, each having a Δ -shaped projection D' on its upper surface and on which impinges the beveled edges of the vertical wedges C' and annular ring B when it is screwed down until 70 their lower edges are even with each other. If the lower edge of annular ring B should be screwed below the edge of the wedges C' and secured by jam-nut R, the tool-holders D would be moved toward the center, thus 75 decreasing the diameter of the cutting edges of tools L, and to increase the diameter of cutting edges the vertical wedges C should be lowest, as the beveled edges being thrust downward on the projection D' would force 80 the tool-holders outward until the opposite side of projection D' would come in contact with the bevel on the annular ring, and as all the tool-holders are on the same plane they are all moved laterally in unison. The tools 85 L are pieces of square steel cut to a proper length and with suitable cutting edges are secured in tool-holders D by a small set-screw D². For setting the tools L a gage is used to insure each projecting a uniform distance 90 from the face of tool-holder D. The outside lower edge of annular ring B is graduated into one hundred and twenty-five divisions, and one turn of the ring B on the threads of the vertical wedges C makes a difference of 95 100

one-eighth inch in their relative positions, (there being eight threads per inch,) and the angle of the projections D' being forty-five degrees each of tool-holders are moved one-half of this distance laterally, or one-sixteenth inch each. If moved only one graduation, the distance the tools moved would be only one hundred and twenty-fifth of one-eighth inch, or one one-thousandth of an inch. A fixed pointer P is secured to the body A, at which point is indicated the amount of adjustment.

To assemble the different parts of the boring-tool, the tool-holders D are placed in the lateral openings A' until the inside edges of the projections D' touch the body A. Place the vertical wedges C in the recesses C', with their lower edges resting on the projections D'. Screw the annular ring B over the top part of body A and continue down the threads of the vertical wedges C until its lower beveled edge also rests on the bevel of projection D' on the tool-holders. The jam-nut R is then screwed on the body A until its lower edge impinges on the top of annular ring B, forcing it downward on the projections D' and securing them all in the same radius from center of tool. A hole F is shown bored upward in the center of tool and tapped, so that a center can readily be applied for adjusting work to the center of the boring-cutters or adjusting the center of platen on a drill-press.

One of the uses to which this boring-tool can be applied is the boring of car-wheels, where a quantity may all be bored to same size without changing the tool, and if slight variations in size are necessary when fitting wheels on second-hand axles it can readily be done by caliperizing the wheel fit of axle and measuring same with vernier-caliper and then measure the last wheel bored. The difference is made by simply loosening the jam-nut R and setting the proper graduation-marks on the annular ring B opposite to the pointer and then securing the jam-nut R again in its place.

In boring holes where the bottom is larger in size than the top this tool can be used, as the diameter can be changed without withdrawing the cutting edges from the hole being bored.

Having described my invention, I claim as follows:

1. An expansion boring-tool having a body with lateral openings, and side recesses, in combination with vertically-disposed wedges seat-

ed in the recesses and having threads on one side, a ring threaded on the wedges, tool-holders in the lateral openings and means on the tool-holders engaged by the wedges and ring whereby the operation of the wedges and ring adjusts the tool-holders and means for retaining the ring in its adjusted position.

2. In an expansion boring-tool, a body having a transverse toolway, a tool-holder in said way having a projection, wedges arranged to bear upon opposite sides of said projection and relatively movable to project or retract the tool-holder and means for holding the wedges in adjusted positions.

3. An expansion boring-tool having a body provided with lateral openings, tool-holders seated in the lateral openings, and having projections with oppositely-disposed camming-surfaces, a ring on the body frictionally engaging the projections of the tool-holders, members coacting with the ring on the projections of the tool-holders, means for connecting the ring and members so that movement of the ring communicates movement to the members in the opposite direction, and means for holding the ring in an adjusted position.

4. In an expansion boring-tool, a body having lateral openings and longitudinal recesses, tool-holders having inverted-V-shape projections in said openings, an annular ring with a lower beveled edge, wedges seated in the recesses having their ends engaging the projections of the tool-holders, the ring and wedges being threaded together and moved oppositely, means for retaining the ring in its adjusted position.

5. An expansion boring-tool having a body provided with lateral openings and a pointer, tool-holders having projections with camming-surfaces, in the openings, a ring and wedges coacting oppositely on the camming-surfaces, means for holding the ring in adjusted position, the said ring having graduated divisions under the pointer and coöperating means on the ring and wedges for holding them in relative adjustment.

In testimony whereof I have signed my name to this specification in the presence of two subscribing witnesses.

WILLIAM POHLMAN.
